UNITED STATES PATENT OFFICE.

WILLIAM H. CARRIER, OF ADRIAN, MICHIGAN.

DESK ATTACHMENT.

SPECIFICATION forming part of Letters Patent No. 606,514, dated June 28, 1898.

Application filed January 26, 1898. Serial No. 667,991. (No model.)

To all whom it may concern:

Be it known that I, WILLIAM H. CARRIER, a citizen of the United States, residing at Adrian, in the county of Lenawee and State of Michigan, have invented certain new and useful Improvements in Desk Attachments; and I do hereby declare the following to be a full, clear, and exact description of the invention, such as will enable others skilled in the art to 10 which it appertains to make and use the same.

My invention is an improvement in adjustable supports for holding a board for use in reading, writing, or drawing; and it consists in the novel features hereinafter described, 15 reference being had to the accompanying drawings, which illustrate one form in which I have contemplated embodying my invention, and said invention is fully disclosed in the following description and claims.

20 Referring to the drawings, Figure 1 represents a perspective view of a table, desk, or other article having my improved device attached thereto and supporting a board in an inclined position. Fig. 2 is a side view of the 25 device, showing one of its adjusted positions in dotted lines and another in full lines. Fig. 3 is a rear view of the device.

My improved adjustable support consists, essentially, of two members, one of which I 30 term for convenience the "table-clamp" and the other I term the "board-clamp."

The table-clamp consists of a plate A, which is provided with a pair of parallel jaws a , separated sufficiently to allow them to receive the edge of a desk or table of considerable thickness. The lower jaw is provided with a threaded aperture, through which extends a set-screw a' , provided, preferably, with a winged head a^2 at its outer end and at 40 its inner end with a clamping-plate a^3 for engaging the under side of the table or desk, which in this instance is designated D. In order to prevent the plate a^3 from turning with the screw a' , I provide it at one end with 45 rearwardly-extending arms a^4 , which embrace a vertical portion a^5 of the plate A, as shown in the drawings. I prefer to attach the upper end of the screw a' permanently to the plate a^3 by forming an aperture in said plate counter-sunk on its upper side and by upsetting the end of said screw slightly in said aperture, the end of the screw lying below the top

55 face of the plate, so as not to mar the desk or table. The under face of the jaw a above the table D and the upper face of the plate a^3 will preferably be provided with a facing of felt, rubber, or other suitable material to prevent scratching the article to which the clamp may be attached. At the inner end of the upper jaw a the plate A is provided with 60 an aperture a^5 so located that it will be substantially in line with the upper corner of the edge of the desk or table to which the clamp is attached, and the rear portion of the plate A is provided with a curved slot a^6 concentric 65 with the said aperture a^5 .

The board-clamp consists of a plate B, provided with horizontal flanges b , extending on one side of said plate. The upper flange b is provided with a threaded aperture which 70 is engaged by a set-screw b' , having a winged head b^2 , and to the other end of said set-screw is attached a movable clamping-plate b^3 , which 75 is secured to the set-screw in the same manner as above described with reference to the plate a^3 and set-screw a' , and the inner edge of said plate b^3 engages the plate B, thus preventing the clamping-plate from turning with the screw. The plate B is pivotally connected to the plate A by means of a pivot-pin, preferably in the form of a rivet b^4 , which passes through the aperture a^5 in the plate A, and the plate B is provided with an adjusting set-screw b^5 , also having a winged head which 80 passes through the concentric slot a^6 and engages the plate B. It will be seen that by loosening this screw b^5 the board-clamp can be adjusted to different positions with respect to the plate A, and the slot a^6 will be so formed that a board held in the board-clamp B, as 85 shown in the drawings, may be adjusted from a horizontal position to an inclination of nearly ninety degrees.

It will be observed that by means of the adjustable clamping-plate b^3 boards of different 90 thicknesses may be used with my improved device, and when a board is secured in the board-clamp and the table-clamp is secured to a desk or table the edge of the board opposite the clamp will rest upon the edge of the table by reason of the fact that the pivot-pin b^4 is substantially in line with the upper corner of the table edge, as before described, 100 so that the board is supported at one side by

the clamp and at the other side by the table or desk itself. The board will thus be held with great rigidity in any position to which it may be adjusted by the use of a single one 5 of my improved devices.

My improved device is adapted for holding drawing or writing boards, and by its use such boards can be attached to any ordinary desk or table. It is also of great advantage 10 in schools for teaching writing or drawing or in studying, as the user can sit perfectly upright with the board before him at any desired angle and write, draw, or study without stooping.

15 What I claim, and desire to secure by Letters Patent, is—

1. A support comprising among its members, a clamping device adapted to be secured to a desk or other article, having a pair of 20 clamping-jaws, forming a clamping-recess between them, a board-holding device pivoted to said clamping device, substantially in line with the upper and inner corner of said clamping-recess, and means for adjustably securing 25 said board-holding device in different positions, whereby the edge of the board opposite the board-holding device will rest upon the edge of the desk or other article, substantially as described.

30 2. A support comprising among its members, a plate provided with a pair of clamping-jaws, forming a clamping-recess between them, for engaging the edge of a desk or other article, a board-holding device pivoted to said 35 plate substantially in line with the upper and inner corner of said recess, and provided with means for attaching it to one edge of a board, the said plate being provided with a curved slot concentric with the said point of pivoting, 40 and a set-screw passing through said slot and engaging said board-holding device, whereby the edges of the board opposite the clamp will

rest upon the edge of the desk or other article, substantially as described.

3. A support comprising among its members 45 a clamping device provided with clamping-jaws forming a clamping-recess between them adapted to engage the edge of a desk or other article, a board-holding device provided with an adjustable clamp for holding boards 50 of different thicknesses, pivoted to said clamping device, substantially in line with the upper and inner corner of said clamping-recess, and means for adjusting said board-holding device with respect to the clamping device to 55 hold the board in different angular positions, whereby the edge of the board opposite the board-holding device will rest upon the edge of the desk or other article, substantially as described. 60

4. A support comprising among its members, a plate provided with a fixed jaw and an adjustable jaw, forming a clamping-recess between them for engaging the top of a desk or other article, said plate being provided with a 65 pivot substantially in line with the upper and inner corner of said recess, and a curved slot concentric with said pivot and a board-holding device secured to said plate by said pivot and provided with an adjustable clamp for 70 holding boards of different thicknesses, and an adjusting set-screw passing through said slot and engaging said board-holding device, whereby the edge of the board opposite the board-holding device will rest upon the edge 75 of the desk or other article, substantially as described.

In testimony whereof I affix my signature in the presence of two witnesses.

WILLIAM H. CARRIER.
